UNITED STATES PATENT OFFICE.

JACOB BENEDICT, OF GRAND RAPIDS, MICHIGAN.

FURNITURE-CLAMP.

SPECIFICATION forming part of Letters Patent No. 427,035, dated May 6, 1890.

Application filed March 12, 1888. Serial No. 267,044. (No model.)

To all whom it may concern:

Be it known that I, JACOB BENEDICT, a citizen of the United States, residing at the city of Grand Rapids, in the county of Kent and State of Michigan, have invented certain new and useful Improvements in Furniture-Clamps, of which the following is a specification.

My invention relates to clamps designed for use in furniture-factories in setting up articles of furniture and for other similar uses; and its object is to provide in cheap and simple form a clamp adapted to and of sufficient power for such purposes. This object I accomplish by the mechanism shown in the accompanying drawings, in which—

Figure 1 is an elevation of that form of the device used as a bed-clamp. Fig. 2 is a section of the same on line $\alpha\alpha$ of Fig. 1. Fig. 3 is a top plan view of another form of the machine, used for clamping irregular forms. Fig. 4 is a side elevation of Fig. 3. Fig. 5 is a perspective view of the plate or frame which is a part of Figs. 3 and 4. Fig. 6 is a detailed view of the hook used in Figs. 3 and 4; and Fig. 7 is a detailed view of the sliding plate and arm, showing the ball-and-socket joint.

In the drawings, A A of Fig. 1 (the bed-clamp) show the upper and lower rails of the main frame firmly fastened together by the vertical cross-pieces at the ends B B. A second vertical cross-bar B² is placed a short distance from the one at the end and parallel thereto. The two are firmly fastened together and to the frame by the braces L L. These last two vertical bars B B² are duplicated on the other side of the top and bottom rail; and between the pair at the end and of the same thickness as the rails A is the beam C, rigidly held in its position between the adjacent bars B by bolts and strengthened by the tie-rod M. A corresponding beam C' is fitted between the two bars B², but loosely, so as to slide backward and forward therein, and when in use operates as a follower. Toward the other side of the frame is placed the pair of vertical bars B', sliding upon the top and bottom rails and carrying bolted between them the trussed beam C with tie-rod M. These bars are supported by the car-

riage F with wheels G. Back of bar B', upon the upper and lower rails, are sliding blocks H H, with bolts I passing through the blocks and through holes K in the rails. Set-screws J J are inserted through blocks H and bear against the back of the adjacent beam C.

E is a stop, being a vertical bar enlarged at its lower end and vertically adjustable by means of the bolt or set-screw V, passing through a longitudinal slot.

D D' are projecting supports attached to the rear one of each of the two pairs of vertical bars B' B². B'' is also a support for the back of the article to be clamped, being an upright bar extending from the top to the bottom rails and sliding thereon with the guides w w.

The trussed beam C, between bars B, and the follower C' are connected by the elbow-joints O N, N O, of which there are as many as desired, all operated by the rod P. These may be both above and below the operating-lever U. This lever is bolted to a block S, which, if there are elbow-joints both above and below, is double, extending each way from the lever, and the lever U and block S thus make a double bent lever. At each end of S is pivoted a short arm R, which at its other end is pivoted to rod P. In this manner the lever U operates the toggle-joint formed by S R, and that in turn operates through the rod P all the other toggle-joints O N, N O and the follower C'. The block S is pivoted to a portion of the main frame, and this is strengthened by the brace T.

In the modified form of the device shown in Figs. 3 to 7, A' A' are the side rails, resting upon a suitable supporting frame-work. The back piece B''' connects these two rails near their farther end and slides upon the rails longitudinally as ways, being held at any desired point by bolts I' in holes K', and being held down upon the rails by the bolt and nut J'. An additional adjustment may be used, if desired, to take up the space between the holes. The supporting frame-work also carries, at about the same height as the rails and firmly attached to the frame, the bed-piece B''', and to this is bolted the plate 3, which I construct of cast-iron in the form shown in detail in Fig. 5. Upon one side is cast a flange,

which at 6 is broken away and replaced by a ratchet (shown in Fig. 5) and at 7 7 is enlarged into blocks having concave bearings for the convex lower surface of the ends of 5 arms N', making therewith a socket-hinge. Opposite these blocks and upon the face of the plate are flanges 44, which serve as guides for the sliding blocks 11. These have in their upper faces concave sockets 88, with 10 the slots 99 in the surface of the plate between the sockets and the edge, as shown in detail in Fig. 7. The end of the adjacent arm N' is enlarged into the semi-spherical form shown by 7 in Fig. 7. This fits into the socket 15 8, making a joint or hinge, which permits free lateral motion, arm N' having sufficient play in slot 9.

The lever U' is pivoted at a short distance from its end to the plate 3, and arms R' R' 20 are pivoted to the lever at short distances above and below the point of attachment to the plate. These rods R' R' are at their other extremities suitably hinged or pivoted to the short arms N' N', so that the lever and 25 rods R' form toggle-joints operated by the lever, and they through rods R' operate the toggle-joints N' N'. It is evident that when the device is in the position shown by Fig. 5, depressing the lever will force sliding blocks 30 11 along between ways 4 4 toward the rear edge of the plate.

2 in Fig. 6 is a hook, the straight end of which is pivoted to block 1, as shown in Fig. 3, and which extends back over arms N' N', 35 and is bent up over the edge of bar C'', as shown in Fig. 4. This hook, held down by the weight above it, when in use keeps arm N' and ball 7 in socket 8 and prevents any unsteadiness of motion at that point.

40 C'' is a transverse bar or beam sliding upon rails A' A', and acting as a follower, actuated through hooks 2. For adjusting the clamps to irregular forms slots 55 are cut in this follower, and threaded bolts, with hand-wheels 45 J'' J'', inserted. These bolts screw through nuts inside the follower, and the ends of the bolts bear against the work to be clamped, or suitable blocks may be interposed, as shown, at the ends of the bolts in Fig. 3.

50 The operation of my invention, in the form used as a bed-clamp, is as follows: The head-board, for example, is placed upon bottom rail A, between B' and B''. The lever is raised, so as to flex the elbow-joints and withdraw 55 the follower. The head-board is then adjusted to the follower and the back piece B' C D' adjusted to the other side of the head-board and held by bolts I. A closer adjustment can be had by using the set-screws J. The 60 stop E is then brought down upon the upper corner and held there by bolt V. This stop prevents any upward movement, and the back supports D D' B'' hold the work from springing backward. A depression of the lever will 65 then extend all the elbow-joints and force the follower against the head-board with very great power.

For smaller articles the other form is sometimes preferable. In this the article to be clamped—a chair-back, for example—lies horizontally upon the rails A'. The back-piece B''' is adjusted, and screws J'' J'' are adjusted against various parts of the back, if it is of irregular form. A similar adjustment may be had upon the other side, if desired. If the 70 form is regular, these screws J'' J'' will not be used, or will all be adjusted to the same distance. The use of several slots permits these screws to be vertically adjusted. When the lever is lowered, the follower will be moved 75 forward by the hooks in the manner above described and the chair-back firmly clamped. The ratchet 6 will hold the lever in any desired position.

The socket-hinge shown in Fig. 7 I find to 80 be very useful in this device, for the reason that the block is moved by a slight motion of the arm, and the joint does not become loose by use under heavy pressure, as an ordinary pivot is liable to do.

90 The two forms of clamps above shown are suitable for many purposes, and obvious modifications will adapt them to most if not all of the uses desired in furniture or similar factories, as well as to the manufacture of doors 95 or similar articles. Many such modifications will suggest themselves to any mechanic; and I do not desire to limit myself to the precise form or construction shown; but

What I claim, and desire to secure by Letters Patent, is—

1. In a furniture-clamp, the main frame, the follower and its actuating elbow joints and lever, in combination with the back piece for holding the work against the pressure of 105 the follower, such back piece adjustable within the frame to and from the follower, substantially as described.

2. In a furniture-clamp, the main frame, the follower and its operating elbow joints 110 and lever, in combination with the back piece for holding the work against the pressure of the follower, such back piece sliding on the rails of the frame, the bolts and holes for adjusting and holding the back piece, and the 115 set-screws for taking up the space between the holes, substantially as described.

3. In a furniture-clamp, the combination of the main frame, the back piece, the follower and its actuating-lever and elbow-joints, with 120 the back support B'' and its guides w w, whereby it can be adjusted to the proper place to prevent the work from springing backward, substantially as described.

4. In a furniture-clamp, the combination of 125 the main frame, the back piece, the follower and its actuating-lever and elbow-joints, with the stop E, vertically adjustable for preventing the work from springing upward, substantially as described.

5. In a clamp for furniture and similar articles, and in combination with the main frame, the back piece and the follower, the plate 3, with ways or guides on its face, blocks

sliding therein connected to and operating the follower, the elbow-joints actuating the sliding blocks, and the lever pivoted to the plate and operating the elbow-joints, substantially as described.

6. In a clamping-machine for furniture and similar articles, the main frame, the back piece and the follower, in combination with plate 3, with ways or guides on its face, blocks sliding therein connected to and operating the follower, the elbow-joints actuating the sliding blocks, the lever pivoted to the plate and operating the elbow-joints, and the ratchet for holding the lever in clamping position, substantially as described.

7. In a clamp of the class described, the main frame and the back piece, the lever, the elbow-joints operated by the lever, the follower, and hooks connected at one end to the end of the arm of the elbow-joint and at the other end bent up around the follower to force it into contact with the work, substantially as described.

8. In a clamp of the class described, the main frame, the back piece, the follower, and 25 the lever, in combination with the elbow-joint operated by the lever and the sliding block and ways therefor, said block having a concave recess, and the end of the adjacent arm having a convex surface bearing therein, 30 making a socket-hinge, and said block connected to and actuating the follower, all substantially as described.

9. In a clamping-machine of the class described, the main frame, back piece, follower 35 and its actuating-lever and elbow-joints, in combination with the slots in the follower, and set-screws passing through said slots for adjusting the machine to clamp irregular forms, substantially as described. 40

In witness whereof I have hereunto set my hand and seal in the presence of two witnesses.
